BATTEN

Fred Waller, Huntington, N. Y., assignor to Kenyon Instrument Co., Inc., Long Island, N. Y., a corporation of New York

Application February 5, 1944, Serial No. 521,220

12 Claims. (Cl. 114—103)

This invention relates to flexible sheet materials, including sails, airplane wings, windmill blades, etc., and has for its object to provide a new and improved means for controlling the stiffness and curvature of such surfaces and particularly the trailing edges of sails or the like.

Although the invention is widely useful in all of the above fields, I shall, for the sake of simplicity, illustrate it in its specific application to sail battens adapted to be sewed into the fore-and-aft sails of a boat at approximately right angles to the leech to control the shape and stiffness and thereby increase the efficiency of the sail.

Accordingly, a more specific object of the invention is to provide a novel and improved sail batten which will afford sufficient stiffness and rigidity to give the sail any desired contour when in use, but may be rendered flexible to permit the sail to be lowered and furled quickly and neatly without removing the battens therefrom.

Another object is to provide a simple and efficient sail batten with the foregoing advantages, which may be secured or embedded permanently in the sail and will limit the sail to a desirable curvature in either a port or starboard direction.

Still another object is to provide a new and improved batten or stiffener of the above type which is readily adjustable as to stiffness and which, in the case of a cloth sail, wing or the like, will not pinch or otherwise damage the fabric.

Various other objects and advantages will be apparent as the nature of the invention is more fully disclosed.

Although the novel features which are characteristic of the invention are set forth more in detail in the claims appended hereto, the nature and scope of the invention may be better understood by referring to the following description, taken in connection with the accompanying drawings forming a part thereof, in which specific embodiments have been set forth for purposes of illustration.

In the drawings:

Fig. 1 is an elevation of a typical jib headed sail equipped with leech-stiffening battens embodying the invention;

Fig. 2 is a similar view showing the same type of sail equipped with similar but longer battens;

Fig. 3 is an elevation of a typical boom and gaff sail equipped with my leech-stiffening battens;

Fig. 4 is an elevation, partly in section, of a

batten which is particularly adapted for use in fore-and-aft sails of the type shown in Figs. 1-3;

Fig. 5 is a longitudinal section taken on the line 5—5 of Fig. 4;

Fig. 6 is an end view showing the take-up latch employed in Figs. 4-5;

Fig. 7 is a longitudinal sectional view through a sail equipped with a modified batten which gives it an airfoil curvature;

Fig. 8 is an enlarged sectional view of the batten employed in Fig. 7;

Fig. 9 is a longitudinal sectional view illustrating another modification of the invention, including a special latch for varying the adjustment of this batten;

Fig. 10 is a section taken on the line 10—10 of Fig. 9;

Fig. 11 is an end view showing the take-up latch employed in Figs. 9 and 10;

Fig. 12 is a perspective view illustrating the cooperating links or segments of Figs. 9 and 10;

Fig. 13 is a longitudinal sectional view illustrating still another embodiment of the invention;

Fig. 14 is a longitudinal section taken on the line 14—14 of Fig. 13; and

Fig. 15 is a transverse section taken on the line 15—15 of Fig. 13.

In the following description certain specific terms are used for convenience in referring to the various details of the invention. These terms, however, are to be interpreted in accordance with the state of the art.

In Fig. 1, a typical jib headed canvas sail 1, which is spread on the mast 2 and boom 3, has its trailing edge or leech 4 curved convexly, which extends the sail outwardly beyond the dotted straight line 5 joining the apex with the lower trailing corner. Sails of this type frequently have strips of light material, such as wood, known as "battens," inserted in pockets 6 which are sewed in the sail at approximately right angles to the leech to stiffen the sail and make it lie flat.

A feature of my invention resides in the provision of novel and improved articulated battens 7 which may be held permanently in the pockets 6 of the sail, with advantages which will herein-after more fully appear. The batten 7, shown in detail in Figs. 4 and 5, comprises a plurality of rigid mating blocks or segments 8 which, when nested one upon the other somewhat like a series of articulated vertebrae, may be secured

to form a compact elongated unit with the outward appearance of a narrow strip of wood.

The individual blocks 8 are of rectangular cross section, each having on one face a pair of spaced hemispherical bosses or knobs 9, and on the opposite face a pair of similar hemispherical holes or sockets 10 aligned with said knobs. The knobs 9 of each block are adapted to engage in the holes 10 of the adjacent block to center the blocks properly one upon the other as shown in Figs. 4 and 5.

The faces of blocks 8 which contain the holes 10 are each provided with a raised rectangular rim 12 about the edge thereof, and it is this rectangular rim which engages the flat face of the adjacent block 8 when the blocks are stacked and held together as in Figs. 4 and 5. This concentrates the contact between adjacent surfaces of the blocks about the contiguous edges thereof and makes the batten stiffer than it would be if the entire face of each block, which may be somewhat irregular, were to engage the entire face of the adjacent block.

The blocks 8 are held together by a cord 13, preferably of wire, which is strung through parallel holes 14 extending through the blocks centrally of the aligned knobs 9 and their cooperating holes 10, as shown in Figs. 4 and 5. The loop 15 formed by the cord 13 at one of the end blocks 8, at the left end as viewed in Figs. 4 and 5, may be secured to said end block by suitable means such as plastic cement or the like. The opposite end block is provided with a hollow box-like extension 16 having deep semi-circular notches 17 in opposite edges thereof, forming a bearing for the pivot pin 18 of a tightening handle 19. The ends of the cord 13 are securely fastened to an extension 20 of handle 19. This extension 20 is offset from the pivot pin 18 of handle 19, so that, when handle 19 is pivoted to one limiting position against one edge of the box 16 as shown in full lines in Fig. 4, the cord 13 will be drawn taut and the blocks 8 of the batten will be drawn together to form a rigid unit. The extension 20 may set off-center with respect to pivot 18 so that the handle is held in this position by the pull of the cord 13. However, when handle 19 is swung about its pivot 18 to the other limiting position against the opposite edge of box 16, the extension 20 of the handle will swing into the hollow of the box, as indicated by the dotted lines in Fig. 4, thus loosening the cord 13 and disengaging the blocks 8 so that the entire batten becomes limp and flexible. Other tightening means, such as wing nuts, may be used instead of the handle if desired.

The blocks or segments 8 of the battens 7 may be made of wood or of any other suitable material such as light molded plastic. The battens may be sewed permanently into the pockets 6 of the sail and may be adjusted instantly to stiffen the leech as shown in Fig. 1, or longer battens may be employed to stiffen the entire sail as illustrated in Fig. 2.

The battens may be employed to stiffen any kind of sail. For example, Fig. 3 shows a typical boom and gaff sail 21 including the usual gaff rig 22, with short battens 7 secured in the pockets 6 in the manner previously described. When it is desired to furl or reef the sail, in any of these embodiments of the invention, the handles 19 of the battens are flipped to the disengaging position, permitting the battens to be collapsed with the canvas.

Figs. 7 and 8 show a modification of the invention in which a sail 25 is equipped with battens 26 which limit the sail to an airfoil curvature in either a port or starboard direction. The batten 26 comprises a series of blocks or segments 27 strung like a string of beads upon a cord 28 which passes through central aligned holes 29 in the blocks. One end of the cord is knotted at 30 and preferably sealed by plastic cement or the like in a depression 31 in the end block as shown in Fig. 8.

The other end of the cord may be secured to a tightening handle, not shown, which may be the same in structure and function as the handle 15 of Figs. 4-6.

The end of the batten 26 at the left of Figs. 7 and 8 is at the luff or leading edge of the sail 25, while the opposite or right end of the batten is at the leech or trailing edge. The engaging faces of the two blocks 27 nearest the luff end are bevelled or tapered at 33 to form inclines, permitting said blocks to rock upon their apices and assume either an outwardly or inwardly bowed position. The engaging faces of the next 25 succeeding blocks 27, toward the leech or right in Fig. 8, may also be tapered as shown at 34, but these inclines 34 become progressively less and less steep as the blocks approach the leech, until the engaging faces finally become flat toward the leech end as shown in Fig. 8.

The batten 26 of Fig. 8 may be used, for example, in a fore-and-aft sail of the type shown in Fig. 2, and the engaging faces of the series of blocks 27 may be tapered to any desired extent 35 to give the sail the desired airfoil curvature. When the sail is initially set the battens 26 are tightened in the manner described. The sail will then bend or bow either to the port or starboard, according to the direction of the wind. Then, when the boom 3 is swung over as in tacking, the wind automatically bows the sail and rocks the blocks 27 of the battens to the opposite bowed position, the battens at all times limiting the bulge in the sail, as illustrated in Fig. 7. This construction, and modification thereof, may also be used for shaping and stiffening various other types of sails, blades and airfoils, such as windmill arms, airplane surfaces, aquaplanes, wing floats or the like.

Figs. 9 to 13 show another embodiment of the invention, comprising a series of mating blocks or segments 40 having their engaging surfaces formed in a special box-joint type of dovetail which effectively prevents the fabric of the sail or other airfoil from getting caught in the joints as they bend from side to side. All of the blocks 40 except the two at the extreme ends may be cast in the same mold. Each has on one face a central tapered prong 41 and two shorter flat-ended prongs 42 separated by flat grooves 43, and on the opposite face a pair of tapered prongs 44 and central and end grooves 45, as best shown in Fig. 12. These blocks mesh with the central prongs 41 engaging in the flat central grooves 45, and with the twin prongs 44 engaging in the twin flat grooves 43, as shown in Fig. 9. However, the flat end prongs 42 remain spaced from the bottoms of the end grooves 45 of the mating block. Hence it is impossible for a sail or other covering fabric to become pinched between the prongs 42 and their grooves 45 when the joints bend.

The blocks 40 are held together by a cord 47 which is strung through parallel holes in the 75 blocks, as in the construction of Figs. 4-5, the

loop 48 of the cord preferably being secured by an adhesive or otherwise to the block on one end as previously described. The two ends of the cord, which come together at the opposite end of the batten at the right of Figs. 9 and 10 are fastened to a pin 50 adapted to be slipped into one or another of a plurality of spaced notches 49 in the channel-shaped handle 51 of a take-up latch 52, as best shown in Figs. 9 and 11. The take-up latch 52 fits over the outer rim of the hollow box-like extension 53 of the end block 40 at the right of Figs. 9 and 10. The handle 51 is fulcrumed to the latch plate at 54, and the inner edge of the handle channel is bent over at 55, adjacent the fulcrum so that, when the handle is turned down to the limiting position shown in Fig. 9, the cord 47 is drawn taut over the spun edge 55 thereby tightening the blocks 40 of the batten and also locking the handle 51 in this position. The bent over edge 55 is off-center with respect to the fulcrum 54 so that the handle is held in position by the pull of the cord 47.

When it is desired to loosen the blocks 40, for example, for the purpose of furling a sail employing battens of the type shown in Figs. 9 to 12, the handle 51 is simply flipped upward from its locked position. In order to vary the tension on the cord 47 the pin 50 of the cord is slipped into another of the notches 49 in the handle 51, thus varying the adjustment of the blocks 40 as desired. Although, as stated above, all of the blocks 40 except the end blocks may be cast in a common mold, the angles of the various tapered prongs 41 and 44 may be varied by sandpapering or by other suitable means so that the pitch will vary from block to block to permit the batten to assume any predetermined curvature. It will be evident that the batten or stiffener of Figs. 9 to 12, like the others previously described, may be used for a wide variety of purposes where it is desired to control the curvature of a flexible surface.

Figs. 13 to 15 illustrate still another modification of the invention, wherein each of a plurality of mating blocks or segments 57 is provided on one face with a pair of spaced tongues 58 and on the opposite face with aligned grooves 59 adapted to receive the tongues of the adjacent block 57. Within each groove 59 is a centrally disposed cylindrical hole 60 through which passes the looped connecting cord 61 which is similar to the cords previously described. Within each hole 60, surrounding the cord 61, is a coil spring 62 which projects outwardly into the groove 59 and engages the edge of the adjacent tongue 58.

In this embodiment of the invention the extent of the separation of the blocks 57 may be controlled by varying the compression of the springs 62, which, in turn, may be regulated by varying the tension on the cord 61. The maximum angular displacement of the blocks, or the curvature of the batten, is determined by the separation of the blocks because each pair of blocks may deflect until the corners engage as shown in Fig. 14.

The shape of the curve may be controlled by varying the relative strength of the springs 62 in the different blocks. When the cord 61 is tightened the various springs will be compressed by an amount inversely proportional to their respective moduli. Hence the blocks containing the stronger spring will be held apart a greater distance than the blocks containing the weaker springs and will take a correspondingly greater curvature before their corners engage and limit their movement. Any desired curvature may be

obtained by proper selection of springs and by suitable adjustment of the cord 61. For an airfoil curvature as shown in Fig. 15 the springs are made successively weaker from left to right.

5 In this embodiment the batten may be made completely rigid and straight by tightening the cord 61 sufficiently to compress all of the springs and bring the block surfaces in contact as in Figs. 4 and 5.

10 The blocks are arranged so that the tongues and grooves remain dovetailed and do not completely separate when the cord 61 is released. The tongues and grooves thus serve to hold the blocks in vertical alignment as well as to prevent the covering fabric from being pinched between adjacent blocks when they are tightened or when their corners engage due to flexing of the batten.

20 Stop means may be provided to limit the separation of the blocks or the cord 61 may have stop means to limit its movement in the blocks. The various springs may be secured in the holes 60 as by cement or plastic to prevent them from falling out when the blocks become separated.

25 It is to be understood that the above examples are only illustrative and that various changes and modifications may be made therein and that the invention is capable of various uses which will be readily understood by a person skilled in the art.

30 What is claimed is:

1. A sail batten comprising an elongated series of blocks arranged end to end with abutting end surfaces, a cord strung through said blocks normally holding said batten in non-rigid condition, means to tighten said cord to secure said blocks together in a stiffened unit, at least some of said blocks having tapered engaging surfaces permitting limited flexing of said unit, and means adjusting the tension of said cord to vary the flexing of said unit.

2. A sail batten comprising an elongated series of blocks arranged end to end with abutting end surfaces, a cord strung through said blocks and adapted when loose to permit said batten to flex at will, and means for tightening said cord to secure said blocks together in a stiffened unit.

3. A sail batten comprising an elongated series of blocks arranged end to end with abutting end surfaces, a cord strung through said blocks and adapted when loose to permit said batten to flex at will, and means including an adjustable handle at one end of said batten for tightening said cord to secure said segments together in a stiffened unit.

4. A sail batten comprising an elongated series of blocks arranged end to end with abutting end surfaces, a cord strung through said blocks and adapted when loose to permit said batten to flex at will, means for tightening said cord to secure said segments together in a stiffened unit, and cooperating prongs and recesses on the respective engaging ends of said segments for aligning the same.

65 5. A sail batten comprising an elongated series of blocks arranged end to end with abutting end surfaces, said blocks having on their respective engaging ends a pair of spaced sockets and a pair of spaced prongs mating therewith for aligning said blocks, a cord strung through said blocks and adapted when loose to permit said batten to flex at will, and means including an adjustable member at one end of said batten for tightening said cord to secure said blocks together in a stiffened unit.

6. A sail batten comprising an elongated series of blocks of generally rectangular cross section arranged end to end, said blocks having on their respective engaging ends a plurality of spaced transverse grooves and a plurality of spaced transverse prongs mating therewith for aligning said segments, a cord strung loosely through said blocks and adapted when loose to permit said batten to flex at will, and means engaging the cord at one end of said batten for tightening said cord to secure said segments together in a stiffened unit, the inner prongs of said segments having tapered engaging end surfaces to rock in their mating grooves and thereby limit the curvature of said batten.

7. A sail batten comprising an elongated series of blocks of generally rectangular cross section arranged end to end, said blocks having on their respective engaging ends a plurality of spaced transverse grooves and a plurality of spaced transverse prongs mating therewith for aligning said segments, a cord strung loosely through said blocks and adapted when loose to permit said batten to flex at will, and means engaging the cord at one end of said batten for tightening said cord to secure said segments together in a stiffened unit, the inner prongs of said segments having tapered engaging end surfaces to rock in their mating grooves and thereby limit the curvature of said batten, and the outer prongs of said blocks being sufficiently short to provide clearance at their ends to avoid pinching the sail in their mating grooves.

8. A sail batten comprising an elongated series of blocks arranged end to end, compression springs disposed between adjacent blocks to control their separation, a cord strung through said blocks and adapted when loose to permit said batten to flex at will, and means for tightening said cord to compress said springs and limit the spacing of said blocks so as to correspondingly limit the extent of the flexibility of said batten.

9. A sail batten comprising an elongated series

of blocks arranged end to end, compression springs disposed between adjacent blocks to control their separation, a cord strung through said blocks and adapted when loose to permit said batten to flex at will, and means for tightening said cord to compress said springs and limit the spacing of said blocks so as to correspondingly limit the extent of the flexibility of said batten, the springs being of decreasing stiffness along

10 said batten to produce an airfoil curvature.

10. A sail batten comprising an elongated series of blocks arranged end to end, said blocks having on their respective engaging ends a plurality of spaced transverse grooves and tongues mating for aligning said blocks and preventing pinching of said sail between adjacent blocks, compression springs between adjacent blocks to control their separation, a cord strung through said blocks and adapted when loose to permit said batten to flex at will, means for tightening said cord to compress said springs and limit the spacing of said blocks so as to correspondingly limit the curvature of said batten.

11. A flexible sheet material having an elongated pocket, a stiffening batten in said pocket comprising an elongated series of blocks arranged end to end with abutting end surfaces, and a cord strung through said blocks to secure the same in non-rigid condition and means to tighten said cord to secure said blocks in a stiffened unit so as to limit the flexibility of the sheet material.

12. In a sail, a stiffening batten comprising an elongated series of blocks arranged end to end with abutting end surfaces, and a cord strung through said blocks to secure the same in non-rigid condition and means to tighten said cord to draw said blocks together in a stiffened unit, at least some of said blocks having tapered engaging surfaces to permit limited flexing of said batten and the covering surface.

FRED WALLER.
